(57) **CLAIM**

The ornamental design for an outsole of shoe, as shown and described.

DESCRIPTION

FIG. 1 is a perspective view of an outsole of the present invention.

FIG. 2 is a side view of the sole shown in FIG. 1.

FIG. 3 is an opposite side view of the outsole shown in FIG. 1.

FIG. 4 is a top view of the outsole shown in FIG. 1.

FIG. 5 is a bottom view of the outsole shown in FIG. 1.

FIG. 6 is a rear view of the outsole shown in FIG. 1; and, FIG. 7 is a front view of the outsole shown in FIG. 1.

The broken lines on the outsole depict unclaimed parts of the outsole and form no part of the claimed design. The broken line showing of a shoe upper is for purposes of showing environmental structure associated with the outsole in a condition of use, and also forms no part of the claimed design.
